UNITED STATES PATENT OFFICE.

ARNOLDUS ALOYSIUS VERHOEVEN, OF TILBURG, NETHERLANDS.

MACHINE FOR MIXING OR WORKING UP DOUGH AND OTHER MATERIALS.

1,201,776.

Specification of Letters Patent.

Patented Oct. 17, 1916.

Application filed December 12, 1914. Serial No. 876,928.

To all whom it may concern:

Be it known that I, ARNOLDUS ALOYSIUS VERHOEVEN, a citizen of the Netherlands, residing at Lange Nieuwstraat 25, Tilburg, the Netherlands, have invented new and useful Improvements in Machines for Mixing or Working Up Dough and other Materials, of which the following is a specification.

This invention relates to machines for mixing or working up dough, paste and other materials, and has reference to improvements in that type of such machines in which the mixing is effected in troughs placed in front of the machine by means of a mixing tool or agitator proper removably attached to one of the extremities of a two-armed lever, which lever is pivoted so as to oscillate in two planes, the consequence being that the tool describes a closed path.

Various constructional forms of mixing machines of this description have already been suggested but with these constructions the mixing or agitating mechanism has been so connected by means of toothed gearing or other equivalent devices with the driving mechanism that the outer extremity of the beforementioned pivoted lever could only describe one predetermined circle. In some of these constructions the extremity of the lever was directly connected to a hub cast with a toothed wheel forming part of the driving mechanism while in other cases the extremity of the said pivoted lever was connected to a forked rod, the other end of which terminated in a sphere, which sphere rested, as to a portion of its periphery, in a corresponding recess in the toothed wheel. It will be seen that with all these constructions the outer extremity of the pivoted lever could only describe a single predetermined circular path, in other words that the mixing tool could only follow one predetermined curved path in the trough. This involved the drawback that it was necessary to employ a different machine for a different size of trough, not only causing considerable expense but rendering it necessary to provide several mixing machines in a single installation and causing considerable loss of time.

My present invention relates to an improved construction of mixing machine of the type under consideration in which a single machine can be employed with troughs of various sizes.

In carrying out the invention the pivoted

lever having two arms and carrying at one end the mixing tool proper is connected at the other end with the extremity of a curved sliding piece which piece is adapted to be slid and fixed with respect to the extremity of a spindle in connection with the driving mechanism so that the radius of the circular path described by the end of the two-armed lever can be varied. The sliding piece may be provided with a cylindrical or spherical end engaging in a corresponding recess in the end of the two-armed lever. With this construction the mixing tool may be caused to follow paths of various dimensions.

One method of carrying out the invention is illustrated by way of example in the accompanying drawing, in which:

Figure 1 is a side elevation of the machine, partly in section; Fig. 2 shows the curved rod to a larger scale; Fig. 3 is a plan of a detail.

1 is the framework of the machine, at the lower part of which is located an electric motor 2, the drive being effected by means of a belt passing around the pulley 3 in connection with the motor and around the driving pulley 4. The driving pulley 4 is rigidly attached to a shaft, which shaft carries a toothed wheel 5, meshing with another toothed wheel 6 keyed to a shaft 7. The shaft 7 is provided at one end with a head or boss 8 having an opening at right angles to the axis of the shaft (see Fig. 3). Through this opening passes a rod 9 bent into the form of an arc of a circle. This rod 9 is fixed with respect to the head or boss 8 by means of an adjusting set screw 10. The rod 9 is provided at one end with a cylindrical head 11 engaging in a corresponding opening or recess provided at one end of the two-armed lever 12. This two-armed lever 12 is rockable about a pivot 13, which pivot is carried by a fork at the end of a vertical spindle 14 rotatably mounted upon the framework 1.

At the other end of the lever 12 is detachably mounted the agitating or mixing tool proper, 15, which in this case is formed from a bent rod with a suitably shaped end.

As will be seen from the drawing, the end of the tool follows a closed path so that the material to be mixed is agitated and kneaded to suit requirements.

As has been mentioned already with mixing machines as usually constructed, it is

impossible to alter, according to requirements the closed curved path described by the end of the tool 15, that is to say to make it larger or smaller. The improved construction which renders the alteration of the dimensions of the said path possible, enables any desired quantity of material to be dealt with in an economical manner and the machine can be adapted for use with troughs of different sizes. This is rendered possible by the adjustability of the arc-shaped rod 9, the cylindrical head 11 upon which the rod can be made to follow circular paths of different dimensions by sliding the rod 9 with respect to the head or boss 8, thus varying the circle described by the end of the two-armed lever 12.

What I claim and desire to secure by Letters Patent of the United States of America is:—

1. In a mixing machine the combination of a two-armed lever so pivoted that it can oscillate in two planes at right angles to one another, a mixing tool carried at one end of the lever, a driving axle, an angular rod having one member curved in an arc of a circle and having a sliding connection with the axle, means for adjustably securing the said sliding curved member of the

rod to the axle, and means of connection between the other member of said angular rod and the end of the two-armed lever remote from the mixing tool substantially as described.

2. In a mixing machine the combination of a two-armed lever, a rod rotatable about a vertical axis and having a fork in which the lever is mounted on a horizontal pivot, a mixing tool carried at one end of the lever, a driving axle provided with a head having a transverse slot, an angular rod having one member curved in an arc of a circle and slidably in the said slot, means for locking the said curved member of the rod in any required position in the said slot, a recess in the end of the two-armed lever remote from the mixing tool and a cylindrical projection at the end of the other member of the rod engaging in the said recess substantially as described.

In testimony whereof I have signed my name to this specification in the presence of two subscribing witnesses.

ARNOLDUS ALOYSIUS VERHOEVEN.
